ENGINE STARTER AND GENERATOR MEANS

Samuel Gilbert, Cedar Grove, N. J., assignor to
Bendix Aviation Corporation, Teterboro, N. J.,
a corporation of Delaware

Application August 28, 1946, Serial No. 693,591

17 Claims. (Cl. 74—6)

1

This invention relates to engine starter and generator means, and particularly to means adapting a dynamo-electric machine to operate both as a motor for starting the engine and as a generator driven by the engine.

Such means, of various forms and applications, have heretofore been suggested, which are not limited, as in aircraft applications, as to space and weight considerations, are unduly complicated as to number and character of parts, disposed in inconvenient positions requiring the use of bevel gears and the like, are located in, or necessitate modification of, the engine housings with which they are associated, embody separate gear boxes between the engines and the starters, have starter gearing which operates during the generating period, requires special lubrication and is subject to excessive wear and are subject to other disadvantages.

A prior suggestion for aircraft starters involves the use, in the starter housing, of means for increasing the speed of the dynamo rotor, when operating as a generator, relative to its speed when operating as a motor, which suggestion calls for a circuit of lubricating oil between the engine crank case and the starter housing, thus carrying back into the crank case any metal particles becoming detached from the speed increasing means or other elements of the starter, with consequent likelihood of damage to the engine.

It is an object of the present invention to avoid disadvantages of apparatus of the aforesaid character and to do so by novel effective means.

Another object is to conserve space, weight and cost, over a usual structure in which a starter and a separate generator are mounted on an engine, by novel means rendering the starter also operative as a generator.

Another object is to provide an engine starter and generator unit, in which the starter housing is free from generator speed increasing means therein requiring lubrication by oil from the crank case, and which is effectively sealed against the ingress of the oil.

Another object is to avoid damage to the engine from particles carried thereto from the starter, as by the aforesaid oil circuit.

Another object is to provide means of the aforesaid character adapting the dynamo and engine shafts for end-to-end aligned or parallel relation to each other, to avoid the use of bevel gears and to provide other advantages.

Another object is to avoid the requirement for a separate gear box in a device as aforesaid.

Another object is to facilitate the manufacture,

2

assembly, mounting, replacement and repair of engine starter and generator means.

Another object is to preclude the requirement for an oil lubricating circuit between the starter housing and the crank case and to avoid disadvantages other than that above mentioned resulting therefrom.

Another object is to provide a structure, free from such circuit, in which a dynamoelectric machine is adapted, by simple modification of only a small part of the structure, to have any desired motor and generator speeds.

Another object of the invention is to provide novel engine starter and generator means which is readily adapted for mounting on engines of different existing types without change in the engines, such as an engine having separate mountings for a starter and a generator, respectively, relative to which the device hereof may be mounted either on the starter or the generator mounting, or an engine having a starter mounting, but no generator mounting, on the starter mounting of which the device hereof may be mounted.

Another object is to provide an engine starter-generator, in which the gearing does not operate during the generating period, the necessity for special lubrication is precluded, and excessive wear is prevented.

Another object is to provide a device of the above-indicated character which is simple and durable in construction, economical to manufacture, and effective in its operation.

These and other objects and features of the invention are pointed out in the following description in terms of the embodiments thereof which are shown in the accompanying drawings. It is to be understood, however, that the drawings are for purposes of illustration only, and are not designed as a definition of the limits of the invention, reference being had to the appended claims for this purpose.

In the drawings:

Figure 1 is a side view, partially in section and partially in elevation, of a starter structure and a portion of an engine, illustrating the invention in one form;

Figure 2 is a diagram of electric circuits for the structure;

Figure 3 is a view similar to a portion of Figure 1 showing a modification of the invention requiring change in only a comparatively small portion of the structure of Figure 1; and

Figure 4 is a view similar to Figure 3 of a further modification requiring only a similar slight change.

Referring to Figure 1, the device therein shown, comprises an assembly including, in general, an axially stationary rotatable spline nut 10, a screw shaft 12 in the nut, a starter jaw clutch member 14 adapted, as by a spline connection 16, for rotation with and axial movement relative to the screw shaft 12, a spring 18, means 20 frictionally holding the jaw member 14 for axial movement by the screw shaft 12 through the intermediary of the spring 18 and sealing the starter against the admission of oil from the engine crank case, a rotatable drum 22 having a transverse end wall 23, a disc clutch pack 24 around the drum having alternate or interspersed discs connected to the drum 22 and the nut 10, respectively, and a non-rotative orbital gear 26.

The screw shaft 12, which has coarse thread relation to the nut 10, is limited in its right-hand movement, as shown, by the wall 23 and, in its left-hand movement by engagement of a shoulder 27 on the shaft 12 with a shoulder 29 on the nut 10.

The above-outlined assembly forms a single axial opening 28 through each and all of its aforesaid elements.

The device of Figure 1, further comprises, in general, planet gears 30 carried by trunnions 31 on the wall 23 of the drum 22 and engaging the orbital gear 26, and a driving shaft 32 extending through the opening 28, sealed by a feather seal 33 between the shaft 32 and the drum 22. The shaft 32 is adapted for operation by the engine, through a spline connection 34 to an engine jaw clutch element 36 secured to an engine shaft 38. The shaft 32, as shown in Figure 1, is adapted as an extension attachment of the engine shaft 38 rotatable therewith, and surrounded by the engine jaw element 36.

A rotatable gear member 40 has a sun gear portion 42 carried thereby on a sleeve 43 around a tubular protrusion 44 from the wall 23 of the drum 22, and around the driving shaft 32, which sun gear 42 engages the planet gears 30.

Rotatable means 46, journaled in bearings 48 and 50, carries a pinion 52 engaging the rotatable gear member 4 and having a speed-reducing gear 54 for reducing the speed of an armature shaft 56 when operating as a motor shaft for actuating the jaw member 14.

The shaft 56 is part of a dynamo-electric machine 58, herein referred to as a dynamo, which is operative as a motor and as a generator, the shaft 56 being hollow and aligned with the driving shaft 32, and having a transverse slot 60. Other elements of the dynamo 58, as shown, are generator and motor field windings 59 and 61, respectively, see Figure 2, an armature 63, a commutator 65 and brushes 67.

Centrifugal clutch means 62 includes elements 64 and 66 carried by the driving shaft or engine shaft extension 32 and the hollow armature shaft 56, respectively.

The element 64, which has a hub 69 journaled by a bearing 71 in a stationary support 73, carries shoes 77, in a trough-like perimeter of the element 64, that are held in position by a garter spring 79 radially opposite a flange 81 of the element 66.

A starting pinion 68, rotatable with and axially movable relative to the armature shaft 56 thereon, is connected to the shaft 56, as by a pin 70 extending through the slot 60. A spring 72 operates, between an end member 74 on the shaft 56 and the pin 70, to normally bias the starting

pinion 68 to the right, as viewed in Figure 1, away from the reducing gear 54. A meshing rod 75 is axially slidably disposed in the hollow of the shaft 52 for moving the pin 70 and the starter pinion 68 against the action of the spring 72 to engage the pinion 68 to the reducing gear 54.

A solenoid 76, which is connected in series with the dynamo 58 when the latter is operative as a motor, includes an axially movable core 78 normally spaced from the meshing rod 75, by a gap 80, and adapted to be attracted to a stationary core 82, when the dynamo, conditioned as a motor, and the solenoid are energized to move the meshing rod 74, as aforesaid, to engage the starter pinion 68 to the reducing gear 54.

In other particulars, the structure shown comprises an engine crank case 84 having an opening 86 and a starter mounting portion 88 around the opening 86.

As stated hereinabove, the engine, in this instance, may be of the type adapted to receive a starter, but not a separate generator, in which case the invention, in its form of Figure 1, has a housing 90 including a flange 92 secured to the engine by studs 94.

If the engine of Figure 1, were of the type having another opening similar to the opening 86 and a mounting similar to the mounting 88 for receiving a generator, the latter opening 31 would be closed by a plate. It will later appear herein how the invention may be adapted to fit the generator opening and mounting, in which case the starter opening would be closed by a plate.

The housing 90 comprises a shell-like inner end portion 96 having a flange 98 secured, with the housing, to the crank case 84 by the studs 94, and independently of the bolts to the housing 90, as by screws 100.

The means 20 comprises a yieldable ring-like element 102 of material such as neoprene around a shank portion 104 of the jaw member 14, and has an axial inner portion held tightly against the shank 104, as by a garter spring 106. The means 20 is thus adapted as a unit, not germane to the present invention, having the dual function of sealing the starter against the ingress of oil from the crank case 84, and of frictionally holding the jaw member 14 for action by the screw shaft 12 engaging the latter to the engine jaw element 36. Additional friction means may be provided to augment the friction of the means 20, if necessary or desired.

The drum 22 is journaled, as by a bearing 108, in a portion 110 of the housing 90, which portion 110 has the orbital gear 26 fixed thereto.

Compression springs 112, in the drum 22, act against a ring plate 114 bearing against the discs of the clutch pack 24 and are adjusted by a ring nut 116 screw threaded to the drum therein. A nut 118, on the screw shaft 12, retains the starter jaw member 14 in position.

A portion 120 of the housing 90, having the stationary support 73 as a part thereof and secured to the housing portion 110, as by screws 122, supports the bearing 48 and is secured, as by screws 124, to a dynamo housing portion 126 of the housing 90, between which housing portions 120 and 126 is clamped a partition 128 supporting the bearing 50. Another partition 130, secured to the dynamo housing portion 126, supports a bearing 132 for the armature shaft 56, which has another bearing 134 in an end wall 136 of the portion 126. A casing 138, secured to the

end wall 136 as by screws 140, encloses the cores 78 and 82 and a coil 142 of the solenoid 76.

Referring to Figure 2, the device further comprises a battery 144, a voltage regulator 146, a manually operable switch 148, located as in the cockpit of an airplane, an electrically closed changeover switch 150 for engaging contact members 152 and having a core 154, an actuating coil 156, and a spring 158 biasing the switch 150 to open position.

In operation, with the parts positioned as shown in Figures 1 and 2, as they are when the engine is operating, and when it is not operating, as will appear, assuming that the engine is not operating, and that it is desired to start the engine, the switch 148 is closed by the operator.

This action, referring to Figure 2, establishes a circuit from the positive side of the battery 144, through the switch 148 and the coil 156 to ground, whereupon the switch 150 engages the contact members 152. Also, the coil 142 is connected from the positive side of the battery through the switch 148 to ground.

Energization of the coil 142 attracts the movable armature 78, see also Figure 1, to close the gap 80 and move the meshing rod 74 to the left, as shown.

Engagement of the contact members 152 by the switch 150, establishes a circuit from the positive side of the battery 144 through the motor field winding 61, Figure 2, one of the brushes 67, the commutator 65, the armature 63 and the other brush 67 to ground, thus shunting the generator field winding 59 out of circuit and operating the dynamo 58 as a motor.

Referring to Figure 1, substantially simultaneously with the starting of the dynamo as a motor, the meshing rod 74 pushes the pin 70, against the action of the spring 72, to engage the starter pinion 68 to the speed reducing gear 54, rotation of which is transmitted, through the means 46, to the pinion 52. Movement of the pinion 52 is transmitted to the gear member 40, and by the latter, through its sun gear 42, to the planet gears 30.

Since the planet gears are carried by the drum 22 and engage the stationary orbital gear 26, the reaction caused by this arrangement results in rotation of the drum 22.

Rotation of the drum operates, through the intermediary of the friction clutch pack 24, to rotate the axially fixed nut 10. With the screw shaft 12 splined by the connection 16 to the clutch member 14, and the latter engaged by the friction seal means 20, the first turning of the barrel 22 and the nut 10 causes the screw shaft 12 to advance to the left, from the position shown, to engage the jaw member 14 to the engine jaw element 36, subsequent to which, with the shoulder 27 in engagement with the shoulder 29, the member 14 drives the element 36 and the engine shaft 38 to normally start the engine.

When the engine starts, the jaw clutch element 36 thereof overrides the starter clutch jaw member 14 against the action of the spring 18 and, when the switch 148, Figure 2, is opened, the element 36 cams the member 14 in a usual manner back to the position shown. If the engine shaft 38 for any reason abnormally resists turning, or if the engine backfires, the reaction is absorbed in the starter by the disc clutch pack 24.

When the engine starts, and the switch 148 is opened, as aforesaid, the circuits of Figure 2 are as shown, and the driving shaft 32 rotates at engine speed.

When this speed reaches a predetermined value, the garter spring 79 of the clutch means 62 yields to centrifugal movement of the shoes 77 and the latter engage the flange 81 of the element 66 on the armature shaft 56, whereupon the dynamo 58 is operated as a generator, with its circuits conditioned as shown in Figure 2. Under this condition, with the switch 150 open, the motor field winding 61 is deenergized, and the armature 63 and the generator field winding 59 of the dynamo 58 are connected between ground and the positive side of the battery 144 through the voltage regulator 146.

Referring to Figure 3, in which corresponding parts are designated by corresponding reference numerals, the partial structure, therein shown, illustrates the only changes necessary in the structure of Figure 1 to adapt the invention for cooperation with generator speed increasing gears 166 and 168 in an engine crank case 170. In this instance, the gear 166 is fixed to an engine shaft 172, and the gear 168 is fixed to a stub shaft 174 forming a part of the motor-generator unit.

The latter is generally the same as in Figure 1, with exceptions, such as a housing portion or adapter 176 secured to the housing portion 110 and including a portion 178 enclosing bearings 180, and having a flange 182 secured to the crank case 170. Another exception resides in the fact that, in this instance, a clutch jaw element 184, corresponding to the jaw element 36, instead of being on the crank shaft, is part of the stub shaft 174.

In this form, with the remainder of the unit identical with that of Figure 1, the speed of the generator driving shaft 32 is increased above engine speed and the starting speed of the engine shaft 172 is reduced. By merely changing the ratios of the other gears in the housing 90, the starting speed of the engine shaft 172 may be made the same as in Figure 1.

Also, in the form of Figure 3, the jaw element 36 of the device of Figure 1 may be removed or allowed to remain in place, and the opening 86 of Figure 1 be covered by a plate.

Referring to Figure 4, in which the parts are similarly designated, the partial structure, therein shown, illustrates the only changes necessary in the structure of Figure 1 whereby a generator driving shaft 186, corresponding to the shaft 32, is aligned with an engine shaft 188 for starting the engine at the same speed as in Figure 1, and operating the dynamo as a generator at increased speed.

This result is accomplished by providing an engine clutch or jaw element 190 with an internal gear 192, and planet gears 194 engaging a sun gear 196 and carried by a ring 198 mounted, as by an anti-friction bearing 200, on the shaft 186. A starter clutch/jaw member 202 corresponds to, but, in this instance, is larger in diameter than the member 14 of Figure 1.

Although only three embodiments of the invention have been illustrated and described, various changes in the form and relative arrangements of the parts, which will now appear to those skilled in the art, may be made without departing from the scope of the invention. Reference is, therefore, to be had to the appended claims for a definition of the limits of the invention.

What is claimed is:

1. In an engine starter, the combination of an assembly comprising an axially stationary rotatable nut, a screw shaft in said nut, a starter jaw member adapted for rotation with said axial

movement relative to the screw shaft, a rotatable drum, a disc clutch pack having discs connected to said drum and said nut, respectively, and a non-rotative orbital gear, said assembly forming a single axial opening through its aforesaid elements, planet gears carried by said drum and engaging said orbital gear, a driving shaft extending through said opening and adapted for operation by the engine, a rotatable gear member carrying a sun gear portion around said driving shaft engaging said planet gears, rotatable means carrying a pinion engaging said rotatable gear and having a speed-reducing gear, a dynamo operative as a motor and as a generator and including a hollow armature shaft aligned with said driving shaft and having a transverse slot, centrifugal clutch means having elements carried by said driving shaft and said hollow armature shaft, respectively, a starting pinion rotatable with and axially movable relative to said hollow shaft, means including a meshing rod in said hollow shaft connected through said slot to said starting pinion, means normally biasing said starting pinion away from said reducing gear, and a solenoid in series with said dynamo when operative as a motor and adapted to actuate said meshing rod to engage said starting pinion to said reducing gear.

2. In an engine starter, the combination of an assembly comprising an axially stationary rotatable nut, a screw shaft in said nut, a starter jaw member adapted for rotation with and axial movement relative to the screw shaft, a rotatable drum, a disc clutch pack having discs connected to said drum and said nut, respectively, and a non-rotative orbital gear, said assembly forming a single axial opening through all of its aforesaid elements, planet gears carried by said drum and engaging said orbital gear, a driving shaft extending through said opening and adapted as an engine shaft extension attachment rotatable therewith surrounded by an engine jaw element, a rotatable gear member carrying a sun gear portion around said engine shaft extension engaging said planet gears, rotatable means carrying a pinion engaging said rotatable gear and having a speed-reducing gear, a dynamo operative as a motor and as a generator and including a hollow armature shaft aligned with said extension and having a transverse slot, centrifugal clutch means having elements carried by said extension and said hollow armature shaft, respectively, a starting pinion rotatable with and axially movable relative to said hollow shaft, means including a meshing rod in said hollow shaft connected through said slot to said starting pinion, means normally biasing said starting pinion away from said reducing gear, and a solenoid in series with said dynamo when operative as a motor and adapted to actuate said meshing rod to engage said starting pinion to said reducing gear.

3. The combination with an engine comprising a generator drive gear train including an engine speed input gear and a higher speed output gear, of a starter comprising an assembly including an axially stationary rotatable nut, a screw shaft in said nut, a starter jaw member adapted for rotation with and axial movement relative to the screw shaft, a rotatable drum, a disc clutch pack having discs connected to said drum and said nut, respectively, and a non-rotative orbital gear, said assembly forming a single axial opening through all of its aforesaid elements, planet gears carried by said drum and engaging said orbital gear, a jaw element adapted to be carried with said out-

put gear for cooperation with said jaw member to start the engine, a driving shaft extending through said opening and adapted for connection to said output gear, a rotatable gear member carrying a sun gear portion around said driving shaft engaging said planet gears, rotatable means carrying a pinion engaging said rotatable gear and having a speed-reducing gear, a dynamo operative as a motor and as a generator and including a hollow armature shaft aligned with said driving shaft and having a transverse slot, centrifugal clutch means having elements carried by said driving shaft and said hollow armature shaft, respectively, a starting pinion rotatable with and axially movable relative to said hollow shaft, means including a meshing rod in said hollow shaft connected through said slot to said starting pinion, means normally biasing said starting pinion away from said reducing gear, and a solenoid in series with said dynamo when operative as a motor and adapted to actuate said meshing rod to engage said starting pinion to said reducing gear.

4. The combination with an engine comprising a jaw element having an internal input gear of a gear train, of a starter comprising an assembly including an axially stationary rotatable nut, a screw shaft in said nut, a starter jaw member adapted for cooperation with said jaw element and for rotation with and axial movement relative to the screw shaft, a rotatable drum, a disc clutch pack having discs connected to said drum and said nut, respectively, a non-rotative orbital gear, said assembly forming a single axial opening through all of its aforesaid elements, planet gears carried by said drum and engaging said orbital gear, a driving shaft extending through said opening and carrying an output gear member of said train, a rotatable gear member carrying a sun gear portion around said driving shaft engaging said planet gears, rotatable means carrying a pinion engaging said rotatable gear and having a speed-reducing gear, a dynamo operative as a motor and as a generator and including a hollow armature shaft aligned with said driving shaft and having a transverse slot, centrifugal clutch means having elements carried by said driving shaft and said armature shaft, respectively, a ring-like member around said driving shaft in said engine jaw element, an intermediate gear of said train journaled on said ring-like member, a starting pinion rotatable with and axially movable relative to said hollow shaft, means including a meshing rod in said hollow shaft connected through said slot to said starting pinion, means normally biasing said starting pinion away from said reducing gear, and a solenoid in series with said dynamo when operative as a motor and adapted to actuate said meshing rod to engage said starting pinion to said reducing gear.

5. In engine starting means, the combination of an engine crank case, a crank shaft and an element in said case driven by the crank shaft at a predetermined speed, a starter housing having a portion outside said case and a portion therein, means sealing the latter portion against the ingress of oil from the case to the housing, means extending through said sealing means sealed thereby and including a shaft portion in said housing extending in the direction of the engine shaft and carrying connecting means in said case adapted to connect said shaft portion to said element for operation at said speed, means including clutch members operative for action engaging each other and rotation to turn the crank shaft to start the engine and for disengaging each

other after the engine starts, at least one of said clutch members being connected to said connecting means, means including a dynamo-electric machine operative as a motor effecting said rotation when said clutch members are engaged, and means providing for connecting said shaft portion to said dynamo-electric machine when said clutch members are disengaged for driving the dynamo-electric machine as a generator at said speed.

6. In an engine starter, the combination of a shaft adapted to be driven by means in the engine, a dynamo operative as a motor and as a generator and including an armature shaft aligned with said first shaft, an engine starting pinion rotatable with and axially movable relative to said armature shaft, a jaw member having axial movement into engagement with a cooperating jaw element and rotatable to start the engine, means for causing said axial movement, transmission means connected between said starting pinion and said jaw member for rotating the latter and including a friction clutch, and gear reducing means having a reducing gear adapted for operation by said pinion, means normally biasing said pinion out of engagement with said reducing gear, centrifugal clutch means having elements carried by said first shaft and said armature shaft, respectively, and means operative to engage said starting pinion to said reducing gear.

7. In an engine starter, the combination of a shaft adapted to be driven at engine speed, a dynamo operative as a motor and as a generator and including an armature shaft aligned with said first shaft, an engine starting pinion rotatable with and axially movable relative to said armature shaft, a starter jaw member having axial movement into engagement with an engine jaw element and rotatable to start the engine, means for causing said axial movement, transmission means connected between said starting pinion and said jaw member for rotating the latter and including a friction clutch, and gear reducing means having a reducing gear adapted for operation by said pinion, means normally biasing said pinion out of engagement with said reducing gear, centrifugal clutch means having elements carried by said first shaft and said armature shaft, respectively, and means operative to engage said starting pinion to said reducing gear.

8. In an engine starter, the combination of a shaft adapted to be driven from the engine by means exteriorly of the starter at a speed greater than engine speed, a dynamo operative as a motor and as a generator and including a shaft aligned with said first shaft, an engine starting pinion rotatable with and axially movable relative to said armature shaft, a jaw element, a jaw member having axial movement into engagement with said jaw element and rotatable to start the engine, means for causing said axial movement, transmission means connected between said starting pinion and said jaw member for rotating the latter and including a friction clutch, and gear reducing means having a reducing gear adapted for operation by said pinion, means normally biasing said pinion out of engagement with said reducing gear, centrifugal clutch means having elements carried by said first shaft and said armature shaft, respectively, and means operative to engage said starting pinion to said reducing gear.

9. In an engine starter, the combination of means exteriorly of the starter adapted to be driven by the engine at a speed greater than

engine speed, a shaft driven by said means, a dynamo operative as a motor and as a generator and including an armature shaft aligned with said first shaft, an engine starting pinion rotatable with and axially movable relative to said armature shaft, a starter jaw member having axial movement into engagement with an engine jaw element and rotatable to start the engine, means for causing said axial movement, transmission means connected between said starting pinion and said jaw member for rotating the latter and including a friction clutch, and gear reducing means having a reducing gear adapted for operation by said pinion, means normally biasing said pinion out of engagement with said reducing gear, centrifugal clutch means having elements carried by said first shaft and said armature shaft, respectively, and means operative to engage said starting pinion to said reducing gear.

10. In engine starting means, the combination of an engine shaft, an engine starting clutch element adapted for connection to said shaft, a cooperating engine starting clutch member, means for engaging said element and said member to each other to start the engine and disengaging the same after the engine starts, said member being adapted for rotative action when said element and said member are engaged to start the engine, a dynamo including an armature shaft, means for rendering the dynamo operative as a motor to effect said rotative action, a driving shaft extending through said clutch member rotatable relative thereto and adapted for connection to said engine shaft for operation thereby, and means adapted to connect said driving and armature shafts to each other for driving said dynamo as a generator when the engine is running and said element and member are disengaged from each other and to disconnect said driving and armature shafts from each other during starting of the engine.

11. In engine starting means, the combination of an engine shaft, an engine starting clutch element adapted for mounting on said shaft, a cooperating engine starting clutch member, means for engaging said element and member to each other to start the engine and disengaging the same after the engine starts, said member being adapted for rotative action when said element and said member are engaged to start the engine, a dynamo including an armature shaft, means for rendering the dynamo operative as a motor to effect said rotative action, a driving shaft adapted for connection to said engine shaft in alignment therewith and to be driven by the engine shaft at engine speed, said driving shaft being surrounded by said clutch element and extending through said clutch member rotatable relative to the latter, and means adapted to connect said driving and driven shafts to each other for driving said dynamo as a generator when the engine is running and said element and member are disengaged from each other and to disconnect said driving and armature shafts from each other during starting of the engine.

12. In engine starting means, the combination of an engine shaft, transmission gearing adapted for connection to said shaft, an engine starting clutch element adapted for connection to said gearing, a cooperating engine starting clutch member, means for engaging said element and said member to each other to start the engine and disengaging the same after the engine starts, said member being adapted for rotative action when said element and said member are engaged

to start the engine, a dynamo including an armature shaft, means for rendering the dynamo operative as a motor to effect said rotative action, a driving shaft extending through said clutch member rotatable relative thereto and adapted for connection to said engine shaft for operation thereby, and means adapted to connect said driving and armature shafts to each other for driving said dynamo as a generator when the engine is running and said element and member are disengaged from each other and to disconnect said driving and armature shafts from each other during starting of the engine.

13. In engine starting means, the combination of an engine shaft, an engine starting clutch element adapted for mounting on said shaft and having an internal gear portion, a cooperating engine starting clutch member, means for engaging said element and said member to each other to start the engine and disengaging the same after the engine starts, said member being adapted for rotative action when said element and member are engaged to start the engine, a dynamo including an armature shaft, means for rendering the dynamo operative as a motor to effect said rotative action, a driving shaft having a gear portion adapted for engagement with said internal gear portion and extending through said clutch member rotatable relative to the latter, and means adapted to connect said driving and armature shafts to each other for driving said dynamo as a generator when the engine is running and said element and member are disengaged from each other and to disconnect said driving and armature shafts from each other during starting of the engine.

14. In engine starting means, the combination of an engine shaft, an engine starting clutch element adapted for mounting on said shaft and having an internal gear portion, a cooperating engine starting clutch member, means for engaging said element and said member to each other to start the engine and disengaging the same after the engine starts, said member being adapted for rotative action when said element and member are engaged to start the engine, a dynamo including an armature shaft, means for rendering the dynamo operative as a motor to effect said rotative action, a driving shaft having a gear portion and extending through said clutch member rotatable relative to the latter, a gear between and engaging said gear portions, and means adapted to connect said driving and armature shafts to each other for driving said dynamo as a generator when the engine is running and said element and member are disengaged from each other and to disconnect said driving and armature shafts from each other during starting of the engine.

15. In engine starting means, the combination of an engine shaft, an engine starting clutch element adapted for mounting on said shaft and having an internal gear portion, a cooperating

engine starting clutch member, means for engaging said element and said member to each other to start the engine and disengaging the same after the engine starts, said member being adapted for rotative action when said element and member are engaged to start the engine, a dynamo including an armature shaft, means for rendering the dynamo operative as a motor to effect said rotative action, a driving shaft having a gear portion and extending through said clutch member rotatable relative to the latter, a gear between and engaging said gear portions, means responsive to a predetermined speed of said driving shaft for connecting the latter to the armature shaft for driving the dynamo as a generator, and means adapted to disconnect said driving and armature shafts from each other during starting of the engine.

16. In engine starting means, the combination with an engine shaft, and a gear train including a gear wheel carried by the engine shaft and a gear connected to said wheel, of an engine starter containing a clutch element carried with said gear, a starter clutch member, means adapting said element and member for action engaging each other and rotation to start the engine and for disengaging each other, means including a dynamo-electric machine operative as a motor through the intermediary of said gear train effecting said rotation when said element and member are engaged, driving means connected to said gear, and means providing for connecting said driving means to said dynamo when said element and member are disengaged.

17. In engine starting means, the combination with an engine shaft, and a gear train including a gear wheel carried by the engine shaft and a gear connected to said wheel, of an engine starter containing a clutch element carried with said gear wheel, a starter clutch member, means adapting said element and member for action engaging each other and rotation to start the engine and for disengaging each other, means including a dynamo-electric machine operated as a motor effecting said rotation when said element and member are engaged, driving means connected to said gear, and means providing for connecting said driving means to said dynamo when said element and member are disengaged.

SAMUEL GILBERT.
